UNITED STATES PATENT OFFICE.

LATHAM H. BRIGHTMAN, OF COLUMBUS, OHIO.

ROD-Straightening Device.

1,278,299.

Specification of Letters Patent. Patented Sept. 10, 1918.

Application filed November 18, 1916. Serial No. 62,233.

To all whom it may concern:

Be it known that I, LATHAM H. BRIGHTMAN, a citizen of the United States, residing at Columbus, in the county of Franklin and State of Ohio, have invented certain new and useful Improvements in Rod-Straightening Devices, of which the following is a specification.

My invention relates to rod straightening devices of the type designed for use particularly in connection with high carbon steel bars or rods. My invention is particularly adaptable for use in the art of making nut blanks, in which case a metal rod of proper section is passed and re-passed through the machine until it has been caused to assume a shape substantially straight throughout its entire length.

The main object of my invention resides in the provision of a set of rolls comprising a pair arranged in longitudinal alinement with the machine and a pair of intermediate rolls located between and to one side of the first named pair of rolls, the arrangement being such that this first named pair of rolls may be adjusted relatively so as to increase or decrease the distance between them and to also vary the distance one of these rolls is from the intermediate rolls. In other words, it is aimed to so construct the machine that the two rolls comprising the longitudinally alining pair, may be unequally spaced in distance from the intermediate rolls.

A further object of my invention resides in a vertically as well as horizontally adjustable roll to be used in connection with the three rolls mentioned above, in order to prevent buckling of the stock bar as it is passed through the machine.

Other objects of my invention will appear in a further detailed description of the accompanying sheets of drawings, in which similar characters of reference designate corresponding parts, and in which:

Figure 1 is a top plan view of my rod straightening machine.

Fig. 2 is a section taken on line 2-2 of Fig. 1 and looking in the direction of the arrow.

Fig. 3 is a section taken on line 3-3 of Fig. 1 and looking in the direction of the arrow.

Fig. 4 is a side elevation looking from the left of Fig. 1, and,

Fig. 5 is a diagrammatic view illustrating the manner in which my machine is used.

In these several views, the machine is shown as comprising two bed plates designated 1 and 2 respectively, held spaced from each other by a proper arrangement of framework 3. The entire machine is supported upon the ground in any desired manner, such as the four supporting legs shown at 4. Arranged in longitudinal alinement with the machine as a whole and carried above the upper bed plate 1 are a pair of rolls 5 and 6 mounted respectively on vertically disposed shafts 7 and 8. These rolls have their faces grooved to assume the desired shape as is shown at 9 and are themselves mounted on the reduced portions 10 of these shafts to be held in position thereon by means of the washers 11 and cap screws 12. Both base plates are cut away as is shown at 13 to form guideways into which the slideable bearing members 15 are arranged to fit, these bearing members being preferably under the control of adjusting screws 16 rotatably secured to these slideable bearings by means of the structure shown at 17 and also held in threaded engagement with the brackets shown at 18. Thus, a turning of the screws 16 by means of a socket wrench or crank applied to the squared ends 19 of these screws will cause their movement through the brackets 18 and, in turn, cause a movement of the slide bearings either in or out of the slots or guideways 13. In order that both slideable bearings for each roll may be moved simultaneously, the screws 16 are each provided with a sprocket wheel 20 over each pair of which a chain 21 is designed to pass. Thus, by turning one of the screws 16, these screws operating in connection with the upper and lower slide bearings, one end of the machine will be caused to move in or out as the case may be.

Located intermediate these longitudinally alining rolls and spaced on either side of them are a pair of transversely alining rolls 22 and 23 mounted respectively on upright shafts 24 and 25. These shafts are also reduced on their upper ends as shown at 26 and the rolls themselves held in position by means of the washers 27 and cap screws 28. The arrangement of mounting these shafts is similar to that described for the shafts 7 and 8, in that guideways 29 are provided in

which the slideable bearings 30 and 31 move. Outwardly extending brackets 32 are also provided with which the screws 33 have threaded engagement, the inner ends of 5 these screws being attached to the slide blocks in the manner described in connection with the slide bearings 15. The opposite ends of these screws 33 are also provided with sprockets 34 over which chains 35 operate, the screws themselves being provided at their ends with hand wheels 36 in order to move the rolls 22 and 23 toward or away from the center of the machine.

Thus it will appear that there are two sets 15 of rolls, 5 and 6, and 22 and 23, all coöperating in such manner that two operators may use the same machine to cause it to perform the functions of two machines. The stock bar is fed through the machine in one direction 20 coöperating with the rolls 5 and 6, which both rotate in the same direction and with the roll 23 which rotates in the opposite direction to an operator who stands on the opposite side of the machine and he in turn 25 then instead of returning the bar to be again fed through the machine, returns it by causing it to coöperate with the same rolls 5 and 6 and the roll 22 which rotates in the same direction as the roll 23. It will thus appear 30 that by this arrangement, considerable time is saved, as well as floor space.

The extreme lower ends of the shafts 7 and 8 are provided with worm wheels 37 designed to mesh with complementary worms 35 38 carried upon a shaft 39. This shaft is rotatably journaled in suitable bearings or boxes 40 supported from the sides of the machine and it is to this shaft to which power is applied in driving the machine as 40 a whole. Rotation of the shaft 39 causes a turning of the worms 38 and in turn the worm wheels 37 to drive the shafts 7 and 8. If now the stock bar is fed into the machine from the left or right of the machine, 45 as the case may be, and the intermediate rolls 22 and 23 properly adjusted, these stock bars may be distorted to such degree that after passage between the rolls, they will spring back to assume a substantially 50 straight position. The amount of carbon contained in the various steels, of course, has to be considered in the adjustment of the rolls and, where these bars are distorted to some considerable extent, it is oftentimes 55 desirable to locate the longitudinally alining rolls 5 and 6 so that one is farther from the intermediate rolls than the other. This may be accomplished, inasmuch as each of the rolls is adjustable individually. It will 60 be understood that two intermediate rolls are resorted to only in such cases where it is desired to run the stock bar previously sent through the machine, on the other side of the machine, or where two operators are 65 working at the same time. In this latter

case, the rods or bars may be conveniently returned by placing them on top of the roller 41 journaled in brackets as shown at 42. Thus, after the rod has been placed on this roller, a pull on the rod will cause 70 a turning of the roller and this will lessen the amount of labor necessary to return the rod to its starting position.

In cases where flat thin bars are being run through the machine, it is essential that 75 a roller such as is shown at 43 be in engagement with the top surface of the bar in order to prevent its buckling, while its lower surface is in engagement with one of the wearing strips 44. This roller 43 is mounted 80 in a bracket 45 which is adjustable in a horizontal plane through the medium of its slotted connection with the top bed plate as is shown at 46 and is adjustable vertically by means of the bolt 47 operating in 85 the undercut groove 48 in the upstanding leg of this bracket. In this manner, the roller 43 may be adjusted in a horizontal plane or may be adjusted vertically as is 90 desired.

It sometimes happens that the stock bars are purposely bent to some considerable extent, in order that the bend of the entire bar may be in one direction. This is done in the normal working of the same and depends for its efficiency to a great extent 95 upon the skill of the operator. In order to prevent this bar from turning away from the machine after its passage and during its passage through it, the rollers 49 are 100 provided. These rollers are located on opposite sides of the intermediate rolls 5 and 6 and are rotatably journaled in the ends of arms 50 pivotally mounted as at 51 at their opposite ends to the top bed plate 1. 105 These rollers 49 may be adjusted to assume positions nearer the longitudinally alining rolls and also nearer the intermediate rolls by means of the bolts 52 operating in the undercut slots 53 in the top bed plate 1.

From the foregoing description, it will be apparent that I have provided a type of machine, in which a multiplicity of adjustments of the various rolls may be gotten in order to effect the straightening of steel 115 bars of various shapes as is shown diagrammatically in Fig. 5. These rolls may be adjusted so that the longitudinally alining rolls are moved farther apart or closer together as the case may be and so that they 120 are also at different distances from the intermediate rolls. In addition, these intermediate rolls may be adjusted horizontally toward or away from each other in the same manner as described for the longitudinally alining rolls. Thus, the rolls 5 and 6 may be adjusted to any of the positions as indicated, for instance, in dotted lines 125 in Fig. 5, the positions they assume depending upon the irregularity of the rods. If 130

this irregularity is such that it is necessary to bend the rod so that it will assume an arcuate shape, the rolls 5 and 6 are adjusted to the extreme dotted line positions and the roll 22, or 23, as the case may be, is moved toward the first mentioned rolls, so that after the bar has been fed through, it will be bent to assume an arcuate shape. In order to prevent it from occupying too much space, the smaller rolls 49 are used to properly keep it in line. After its passage through the machine in this direction, the bar is turned over and the two rolls 5 and 6 moved toward each other a slight distance and the roll 22 retracted, which causes the rod to be bent in the opposite direction but to a less extent. In this manner, the rod is fed back and forth continually until it assumes a substantially straight position. In case flat thin bars are being passed through the machine, the vertically adjustable roll 43 is resorted to in order to prevent its buckling and finally the rolls 49 may be used to prevent the stock bar from sliding off the machine or tables located at the opposite ends of the machine.

What I claim, is:

1. A rod straightener comprising a pair of rolls arranged to always be in longitudinal alignment with each other, a pair of idle rolls arranged to always be in transverse alignment with each other and located intermediate said longitudinal rolls, means for rotating both longitudinal rolls in the same direction, means for adjusting said first named rolls longitudinally of the machine, and means for adjusting said second named rolls transversely of the machine, all of said rolls being in a common plane which is at right angles to their axes of rotation and all being adjustable in that plane.

2. A rod straightener comprising a pair of rolls arranged to always be in longitudinal alignment with each other, a pair of idle rolls arranged to always be in transverse alignment with each other and located intermediate said longitudinal rolls, means for rotating both longitudinal rolls in the same direction, means for adjusting said first named rolls longitudinally of the machine,

and means for adjusting said second named rolls transversely of the machine, all of said rolls being in a common plane which is at right angles to their axes of rotation and all being adjustable in that plane, all of said rolls being adjustable independently of each other.

3. A rod straightener comprising a pair of rolls arranged to always be in longitudinal alignment with each other, a pair of idle rolls arranged to always be in transverse alignment with each other and located intermediate said longitudinal rolls, means for rotating both longitudinal rolls in the same direction, means for individually adjusting said first named rolls longitudinally of the machine to increase or decrease the distance between them and to move one farther away from said intermediate rolls than the other, and means for individually adjusting said transverse rolls toward said longitudinal rolls equal or unequal distances, all of said rolls lying in a common plane which is at right angles to their axes of rotation and all being adjustable in that plane.

4. A rod straightener comprising a pair of rolls arranged in longitudinal alignment with each other, an idle intermediate roll mounted between and to one side of said first named rolls, means for rotating said longitudinal rolls in the same direction, means for individually adjusting said first named rolls in a horizontal plane to increase or decrease the distance between them so that one is farther away from said intermediate roll than the other, means for adjusting said intermediate roll to move it at right angles to and in the same plane with said first named rolls, a guiding roll on each side of said intermediate roll, and arms in the ends of which said guide rolls are mounted, said arms being pivotally mounted at their opposite ends.

In testimony whereof I affix my signature in presence of two witnesses.

LATHAM H. BRIGHTMAN.
